UNITED STATES PATENT OFFICE.

GEORGE HERBERT BENTLEY AND EDMUND GARDNER APPLEBY, OF WESTMINSTER,
LONDON, ENGLAND.

GAS-GENERATOR.

1,343,995.

Specification of Letters Patent. Patented June 22, 1920.

Application filed July 7, 1919. Serial No. 308,997.

To all whom it may concern:

Be it known that we, GEORGE HERBERT BENTLEY and EDMUND GARDNER APPLEBY, both subjects of the King of Great Britain, 5 residing at 12, The Broadway, Westminster, London, England, have invented new and useful Improvements in Gas-Generators, of which the following is a specification.

This invention relates to apparatus for 10 feeding fuel to gas generators or the like.

According to this invention a drum is so mounted that it delivers fuel centrally into the mouth of the generator and the drum is rotated about two axes at right angles to 15 each other. The drum is mounted upon a horizontal shaft to which is keyed a toothed wheel meshing with a fixed ring of teeth, and upon a frame, in which the drum together with its shaft is carried, is a horizontal ratchet ring adapted to be given by 20 a pawl so that the drum is rotated about a vertical axis by means of the ratchet ring and is also rotated about a horizontal axis by means of the toothed wheel and fixed 25 ring of teeth.

Alternatively the frame is rotated by 30 means of a driving pinion gearing with a rack fixed to the base of the frame and upon the horizontal shaft carrying the drum is a bevel wheel meshing with another bevel wheel on one end of another shaft to the other end of which is fixed a pinion meshing 35 with a fixed rack, so that when the frame is turned the feed drum is actuated.

35 The annexed drawings show apparatus made in accordance with this invention. Figure 1 is an elevation, partly in section, of one apparatus, and Fig. 2 is a plan and Fig. 3 a vertical section of another apparatus. In Fig. 3 pokers for agitating the fuel are also shown, these however are omitted in Fig. 1.

A frame 10 is mounted on ball bearings 101 on the top of the generator, the frame 45 being guided at its upper end by means of rollers 102. Above the frame is an orifice 11 leading to a feed drum 12 of ordinary construction on a shaft 121 adapted to turn in bearings 122. The drum 12, which as before stated is of ordinary construction, is 50 constructed to receive and deliver its contents in the usual way to a distributing cone (Fig. 1) below it. To the shaft 121 is keyed a toothed wheel 123 meshing with a fixed 55 ring of teeth 13. At the top of the frame

10 is a ratchet ring 103, driven by a pawl 14 mounted on a driving lever 141. The escape of gas is prevented at the top of the frame by means of a water seal 15 into which extends a ring 111 on the orifice 11 and at the 60 bottom of the frame 10 is another ring 104 extending into a water seal 16.

In Figs. 2 and 3, the fuel is fed to the generator through an orifice 11 leading to a drum 12 on a shaft 121 adapted to turn in 65 bearings 122 on the frame 10, and upon the shaft 121 is a bevel wheel 123 meshing with another bevel wheel 124 on one end of a vertical shaft 125, on the other end of which is a pinion 126 meshing with a fixed rack 70 127 so that when the frame is turned, the feed drum is actuated. Pokers 17 having flanges 171 are carried on the frame 10, the pokers 17 being hollow and supplied with water for cooling them through pipes 172. 75 Upon each poker 17 is a rack 173 meshing with a toothed ring 18 fixed to a lever 19 upon which is a weight 191 for balancing the weight of the poker. The lever 19 is pivoted at 192 to a bracket 193 carried by 80 the frame 10. The method of balancing the pokers forms no part of the present invention but is the subject of another application.

What we claim is:—

1. In apparatus for feeding fuel to gas 85 generators, a receiving and delivering drum mounted centrally over the mouth of the generator, means for rotating the drum about two axes at right angles to each other 90 and means for distributing the fuel.

2. In apparatus for feeding fuel to gas 95 generators, a frame at the top of the generator, a horizontal shaft carried by the frame, a receiving and delivering drum mounted upon the horizontal shaft centrally over the mouth of the generator, a bevel wheel on the horizontal shaft, means for causing the bevel wheel to rotate, means for rotating the frame and means for distributing the fuel.

3. In apparatus for feeding fuel to gas 105 generators, a frame at the top of the generator, a horizontal shaft carried by the frame, a receiving and delivering drum mounted upon the horizontal shaft centrally over the mouth of the generator, a bevel wheel on the horizontal shaft, a vertical shaft, a bevel wheel upon the vertical shaft meshing with the other bevel wheel, a 110

pinion on the vertical shaft, a fixed rack meshing with the pinion, means for rotating the frame and means for distributing the fuel.

- 5 4. In apparatus for feeding fuel to gas generators, a frame at the top of the generator, a horizontal shaft carried by the frame, a receiving and delivering drum mounted upon the horizontal shaft centrally over the mouth of the generator, a bevel wheel on the horizontal shaft, a verti-
- 10

cal shaft, a bevel wheel upon the vertical shaft meshing with the other bevel wheel, a pinion on the vertical shaft, a fixed rack meshing with the pinion, a rack on the frame 15 and a driving pinion gearing with the rack, and means for distributing the fuel.

In testimony that we claim the foregoing as our invention we have signed our names this 6th day of June, 1919.

GEORGE HERBERT BENTLEY.
EDMUND GARDNER APPLEBY.
